(57) **CLAIM**

The ornamental design for a multifunctional magnetic seam guide as shown and described.

DESCRIPTION

FIG. 1 is a perspective view of a multifunctional magnetic seam guide showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view of a multifunctional magnetic seam guide in a close status. The broken lines depict portions of the multifunctional magnetic seam guide that form no part of the claimed design.

1 Claim, 9 Drawing Sheets(56)
